UNITED STATES PATENT OFFICE.

JAMES F. HARDWICK, OF OWENSBORO, KENTUCKY.

BURGLAR-ALARM.

1,392,326.

Specification of Letters Patent.

Patented Oct. 4, 1921.

Application filed October 1, 1920. Serial No. 413,978.

To all whom it may concern:

Be it known that I, JAMES F. HARDWICK, a citizen of the United States, residing at Owensboro, in the county of Daviess, and 5 State of Kentucky, have invented certain new and useful Improvements in Burglar-Alarms, of which the following is a specification.

The object of my invention is to improve 10 and simplify burglar alarms for residences. Burglarizing residences has always been a very dreaded menace, and has grown to alarming proportions within the past ten years; at any rate it has grown to such an 15 extent that in our larger cities a suitable protection against same is an important question to decide, and is within the mind of nearly every one. Up to the present time there has been numerous devices of this character devised, mostly those of the bell type, 20 and which are very unsatisfactory for many reasons.

Some alarms consist of an electric bell that, when a door or window is opened, will 25 ring continuously and regularly. This is unsatisfactory, principally because many people sleep so soundly that even a continuous bell does not awaken them; in other words, it is not reliable, as it is liable to fail at 30 any time. Instead of the regular continuous ringing of the bell or other form of noise, my invention produces an impulsive alarm, simply by discharging a simple paper cap which is contained and arranged within a 35 small compact device which may be permanently connected to the head casing of the bed room door or any window of the same room and when said door is opened or said window raised, the device will automatically 40 discharge the paper cap, and the impulse in the quiet of the night will positively awaken the persons sleeping in the bedroom, and simultaneously startle the burglar to such a degree that he will think that he was shot 45 at, or it will cause him to become stunned as if he passed through the door the charge will be nearest his head, and if through the window it will produce similar effects. The wonderful advantage of the device is 50 the impulse that it produces; it is reasonable to believe that when a man enters a house for the purpose of robbing same, even though he has in his hand some form of fire arms, he is in a frightened state of mind because 55 of the fact that his motive is wrong, and

naturally there would be incurred the greatest fear, and by hearing a sudden sound similar to a pistol shot, in many instances if he is holding a pistol he is liable to drop it and run, although if this does not happen he will attempt to leave the house as quickly as possible.

A beautiful and scientific advantage of this device is the fact that it is intended to frighten the burglar away and not injure 60 him, this subject has been scientifically discussed and it has been thoroughly decided that no person or persons though they are actually caught in the act of robbing, should be shot, as this would not assist in destroying 65 this difficulty; it has been known that in some instances that burglars have been caught in the act and given a straight forward talk and kindness and released without notifying the authorities, therefore if 70 the burglar is frightened away it will give him cause to think upon higher things in 75 life, and if these devices were universally used he would decide that it would be even useless to attempt a robbery. It can be 80 plainly seen that the use of my device would eventually be the medium by which the evil of burglarizing would be healed.

Another advantage is that it is so extremely simple that it can be manufactured 85 at a very low cost and sold proportionately. Also it may be easily and quickly attached to any door casing or window casing with little or no expense for installing.

In the practical development of this device for the market it may become necessary to make certain minor changes in the details of construction, but without a departure 90 from the principle disclosed.

In the drawings:

Figure 1 is an elevation of a portion of a door and its frame showing one manner of employing my invention;

Fig. 2 is a plan view of the alarm with the door and door frame in horizontal section;

Fig. 3 is a detail perspective view of a portion of the alarm.

The invention consists of a plate represented by the numeral 1, and which is in the form of a channel as shown, said plate having a portion 2 in order to accommodate one end of the shaft 3, another extended portion 4 will accommodate the opposite end of shaft 3, portion 4 containing a fixed bead 5; a coil spring 6 is provided and one end of 110

same has a bearing at 7, while opposite end is connected to the firing lever 8, which is also of the channel type. Firing lever 8 is provided with a riveted hammer 9. Plate 1 having bent portions 10 in order that paper cap 11 may be slipped thereunder and to retain same. Holes 12 are provided for screws for connecting plate 1 to the casing inside of the room and remains stationary with the wall.

The device is placed upon the door casing in a position in order to allow the lever 8 to be pushed over the bead 5, and the force of the spring 6 will cause the hammer 9 to strike in the center of the cap 11 and discharge same. When not in use the device will remain in the position as described after being discharged, and can be easily set by pulling lever 8 to position as shown in Fig. 1. The bead 5 will retain same in said position. The same device may be used for windows, by simply connecting same to the side window casing and connecting an ordinary wood screw into the sash. When said sash is raised the screw will strike the lever 8 and cause the discharge, same as if it were used for the door.

Having thus described the invention, what is claimed as new is:

A burglar alarm comprising a channeled plate provided with spaced ears at one end and having overhanging lips at the opposite end to retain an explosive thereon, said plate being adapted to be secured upon a fixed support, a second channeled plate pivoted at one end between said ears and adapted to extend over a relatively movable object, a spring coiled about the pivotal connection between the two members and having its opposite ends secured to the respectively adjacent plates whereby to swing the second-mentioned plate forcibly onto the first-mentioned plate, and a firing-pin on the free end of the second-mentioned plate, one of the ears on the first-mentioned plate being extended beyond the pivot toward the second-mentioned plate and provided with an inwardly extending projection on its inner side to yieldably engage over the edge of the second-mentioned plate and normally hold the plates in extended relation against the action of the spring.

In testimony whereof I affix my signature.

JAMES F. HARDWICK. [L.S.]
